A. DROUILLARD

CLOSET VENTILATOR

Filed April 19, 1923

UNITED STATES PATENT OFFICE.

ALBERT DROUILLARD, OF WINDSOR, ONTARIO, CANADA.

CLOSET VENTILATOR.

Application filed April 19, 1923. Serial No. 633,091.

To all whom it may concern:

Be it known that I, ALBERT DROUILLARD, a subject of the King of England, residing at Windsor, in the county of Essex, Province 5 of Ontario, Canada, have invented certain new and useful Improvements in Closet Ventilators, of which the following is a specification, reference being had therein to the accompanying drawings.

This invention relates to devices for forcibly extracting the air from water closet bowls, and its object is to provide a device which is simple in construction and cheap to manufacture and which may be very quickly 10 and readily installed upon water closets as commonly constructed, without any change whatever in the closet.

A further object is to provide a device for the purpose which may be readily installed 20 within the space between a water closet bowl and the adjacent wall, by an unskilled person, the construction and arrangement of the device being such as to readily fit within the space and avoid the fittings usually 25 provided in connection with water closets.

A further object is to provide a device which is efficient in operation and is compact in construction so as to take up but little space and is adapted to be so positioned as to be 30 inconspicuous when in operative position. It is also an object to so construct and arrange the suction fan and its casing as to insure against the fouling of the fan by material which may accidentally get into 35 the inlet of the casing and to further construct the casing and mount the motor thereon so that a removable cover may be provided for the casing which may be readily removed without disturbing the motor or 40 suction fan, whereby access may be had to the interior of the casing and the fan may be readily repaired without dismounting the entire device. A further object is to provide certain other new and useful features 45 in the construction and arrangement of parts, all as hereinafter more fully described.

With the above and other ends in view, the invention consists in the matters herein- 50 after set forth and more particularly pointed out in the appended claims, refer-

ence being had to the accompanying drawing in which—

Figure 1 is a side elevation of a water closet bowl and its setting with a device 55 illustrative of the invention applied thereto and in operative position thereon;

Fig. 2 is a plan view of Fig. 1;

Fig. 3 is a sectional side elevation of a device 60 illustrative of the invention detached;

Fig. 4 is a top plan view of Fig. 3 with a 65 cover for the casing partly broken away and in section to show the interior of the casing and the suction fan therein; and

Fig. 5 is a perspective view of the device 70 detached.

In the drawing, 1 indicates a water closet bowl of the usual construction which in the usual manner of installing such a bowl, is placed at a short distance from a room wall 2, with the ordinary water connection 3 between the bowl and a flush pipe 4 leading from any suitable flush tank (not shown). A bowl is provided with the usual seat 5 which is hinge connected as at 6 to the rear part of the bowl, the hinge connection as 75 commonly constructed, supporting, together with knobs 7, the seat at a spaced distance from the upper surface of the rim of the bowl. All of the described parts are old and well known and of the usual construction and form no part of this invention, but are described for the purpose of illustrating the application of the device embodying the invention, to a water closet bowl as commonly constructed and installed. 80

The device embodying the invention comprises a motor 10, which as shown, may be a common form of electric motor, but it will be understood that any suitable motor driven by electric or other power may be 85 employed. This motor is directly secured to and suspended from the bottom of a suitably shaped sheet metal casing 11, within which casing is a suction fan 12 of an old and well known form, said fan being mounted directly upon the projecting end 13 of the motor shaft, said motor shaft projecting upwardly through the bottom of the casing 11 with the fan secured directly to said inwardly projecting end. The body or cen- 90

tral portion of the casing 11 is circular in plan view, to conform to the circular suction fan, and this casing has a laterally projecting arm 14 which forms the air inlet 5 for the casing, said arm 14 curving into the circular portion of the casing at a tangent thereto with the bottom of the arm above the bottom of a circular portion of the casing, said arm being widened toward its free 10 end and gradually tapered in depth so that the air inlet end 15 of this arm will be of a width to fit between the hinges 6 and will be of a thickness to permit of its insertion between the cover 5 and the upper 15 surface of the rim of the bowl. The circular casing 11 is also formed with an air outlet pipe 16 arranged tangential to the circular casing and of a vertical depth equal to that of the casing.

20 As the motor is secured and suspended directly from the fan casing, the device may be installed as a unit without brackets or other supporting means for the motor, the casing and its outlet and inlet arms, or 25 pipes, spanning the space between the closet bowl and the adjacent wall of the room so that the device will be rigidly supported in place by the bowl and wall without the necessity for other supports or fastening means. 30 Due to the tangential arrangement of the inlet and outlet pipes, the fan casing is offset laterally of the inlet, and therefore the device may be readily installed without disturbing the usual flush pipe connections, and 35 the outlet 16 of the casing may be extended through the wall or connected to any suitable flue therein.

As shown in Fig. 5, the casing is provided 40 with a cover 17 having a down turned flange and formed with extensions integral with the cover, which form covers for the inlet and outlet pipes leading to and from the casing. Suitable fastening means, such as screws 18 passing through the down turned 45 flange of the cover, are provided to secure the cover in place, and as the motor is suspended directly from the bottom of the casing and the fan 12 is made fast to the inwardly projecting end of the motor shaft, 50 said fan and motor are supported entirely 55 independent of the cover 17, which may therefore be readily removed without disturbing the other parts, for the purpose of gaining access to the interior of the casing and its inlet and outlet pipes.

The suction fan 12, as shown in Fig. 3, is positioned within the lower part of the casing 11, and the blades of this fan are of lesser width than the depth of the casing, 60 so that a considerable free open space 19 is provided between the upper edge of the fan blades and the cover. The inlet pipe 14 opens into this space 19 above the horizontal plane of the upper edge of the fan and 65 therefore any material which may accidentally

get into the open end of the inlet pipe, may readily pass through the casing above the fan and out through the outlet 16, without becoming entangled in the fan.

As the casing and its inlet and outlet pipes 70 may be very readily formed from sheet metal, and as this casing forms the support for the motor, thus eliminating the necessity for brackets or other supports, the device may be very cheaply constructed, and as it 75 may be installed by an unskilled person, its cost to the user is at the minimum. Obviously, any suitable motor may be used for driving the suction fan, and other changes 80 may be made within the scope of the appended claims, in the construction and arrangement of parts, to provide for the exigencies of the particular installation, without departing from the spirit of the invention, and such changes are contemplated. 85

Having thus fully described my invention, what I claim is:—

1. A water closet ventilator comprising a casing which is circular in plan view and is formed with integral inlet and outlet 90 pipes, said pipes extending laterally from the casing in opposite directions and tangentially from opposite sides of the casing, said inlet pipe being widened toward its inlet end in horizontal section and tapered 95 toward its inlet end in vertical section, said inlet pipe being of lesser vertical width than the vertical depth of the casing, a motor secured to the bottom wall of the casing and having a shaft extending through 100 said wall into the casing, and a horizontally disposed suction fan secured to the inner end of the motor shaft.

2. A water closet ventilator as characterized in claim 1 and wherein the vertical 105 width of the suction fan is less than the vertical depth of the casing to provide a free space between the upper side of the fan and the top of the casing, which space forms a continuation of the inlet to the casing, whereby a free passage for material entering the inlet is provided across and over the fan.

3. A water closet ventilator comprising a sheet metal casing of substantially circular 115 form in plan view, said casing being provided with integrally formed inlet and outlet passages, said outlet passage extending tangentially from one side of the casing and being of a vertical depth equal to that of the 120 casing, and said inlet passage extending laterally from the side of the casing opposite to that from which the outlet extends, said inlet passage being tapered in vertical cross-section from the casing toward its inlet 125 end and being broadened in horizontal section from said casing toward its inlet end, said inlet passage being of lesser vertical width than the vertical depth of the casing and opening into the casing adjacent the 130

upper side thereof, a motor secured to the bottom of the casing and having a shaft extending through said bottom at the axis thereof, and a suction fan secured to the inwardly projecting end of the motor shaft, with the horizontal plane of the upper side of the fan below the horizontal plane of the lower side of the inlet to the casing, whereby a space forming a continuation of the inlet to the casing is provided within the casing above the fan between said fan and the top of the casing.

In testimony whereof I affix my signature in presence of two witnesses.

ALBERT DROUILLARD.
